UNITED STATES PATENT OFFICE.

JAMES MICHAEL SMITH, OF MONTREAL, CANADA, ASSIGNOR OF ONE-HALF
TO ALFRED WILLIAM BELFRY, OF MONTREAL, CANADA.

PRINTING-FRAME.

SPECIFICATION forming part of Letters Patent No. 703,672, dated July 1, 1902.

Application filed March 8, 1902. Serial No. 97,375. (No model.)

To all whom it may concern:

Be it known that I, JAMES MICHAEL SMITH, of the city of Montreal, in the district of Montreal and Province of Quebec, Canada, have 5 invented certain new and useful Improvements in Printing-Frames; and I do hereby declare that the following is a full, clear, and exact description of the same.

My invention relates particularly to photo- 10 graphic-printing frames; and it has for its object to provide a frame of this type which will facilitate the inspection of a print therein and obviate the soiling thereof by finger- 15 ing same while in the frame.

15 The invention may be said, briefly, to consist in providing means for automatically lifting from the negative the portion of the print held thereupon by one of the hinged halves of the back when the device for retaining said 20 half is displaced; also, providing means for supporting the print away from the negative while the frame is open.

For full comprehension, however, of my invention reference must be had to the accompanying drawings, forming a part of this 25 specification, in which like symbols indicate the same parts, and wherein—

Figure 1 is a plan view of the back of a photographic-printing frame constructed according to my invention closed and Fig. 2 is a perspective view thereof with one end open; and Fig. 3 is a detail sectional view taken on line 3 3, Fig. 1.

30 The frame *b* and hinged leaves *c* and *c'*, constituting the removable back, together with the bow-springs *d* and *d'* for retaining the leaves tightly in contact with the negative, may be as usual.

In order to cause the print *f*, retained between the removable back and negative, to 40 be automatically lifted from the negative, I secure the ends of a spring, preferably a bow-spring *g*, to the respective leaves of the back. Upon displacing either of the retaining-springs *d* and *d'* the leaf held thereby will fly back, as shown in Fig. 2, and draw the portion of the print between it and the negative with it, thus obviating the necessity of lifting the print with the fingers and avoiding any 45 chance of its being soiled by finger-marks or crumpled. To facilitate this drawing action

of the leaves, I mount a sucker on the inside face of one or both. The sucker I prefer to use consists of a soft-rubber saucer *i*. In practice I have found that it is only necessary to mount the sucker upon the larger leaf, as that one is almost invariably used. I cause the portion of the print bent out in this manner to be automatically held in that position for inspection by an angular trip device *h*, pivoted at its angle, as at *l*, to the side of the frame adjacent to the leaf *c*, a light retractile helical spring *m* normally yieldingly retaining said angular device with one arm across the edge of said leaf, the end of 55 said arm being offset, as at *j*. Upon the leaf springing out and drawing the print with it it will trip upon the said projecting arm of the angular device and turn same upon its pivot to a position with its other arm projecting across the inner side of the print, thereby retaining it in a position to be inspected without the necessity of touching it with the fingers, while the offset end *j* of the first-mentioned arm prevents it slipping beneath 60 the turned-up leaf of the back. At the leaf is pressed back to its position to retain the print again upon the negative the light spring 65 *m* will cause the trip device to follow said leaf and return to its normal position. 70

It is obvious that while using printing-frames constructed according to the foregoing the print can be viewed without touching it with the fingers and that owing to the automatic turning out of the print caused by 75 the flying back of the leaf a greater amount of work in progress can be viewed in a given time than has been possible heretofore, thus, besides obviating any chance of soiling the work, facilitating its completion. 80

I have found that under certain circumstances, as, for instance, when light-weight sensitized paper is being used, the sucker may be dispensed with and other changes made in the precise construction of my improved 85 frame without departing from the spirit of my invention. 90

What I claim is as follows:

1. In a photographic-printing frame comprising a negative-holder and a removable back for retaining the sensitized paper upon the negative in said holder, the combination 95

with said removable back of means for automatically lifting the sensitized paper from said negative upon the removal of the back, for the purpose set forth.

5 2. In a photographic-printing frame comprising a negative-holder and a removable back for retaining the sensitized paper upon the negative in said holder, the combination with said removable back of means for automatically lifting the sensitized paper from said negative upon the removal of the back; and means for retaining said paper in said position, for the purpose set forth.

15 3. In a photographic-printing frame comprising a negative-holder, a removable back consisting of a pair of leaves, and means for retaining said leaves in contact with said negative, of a retractile spring connected at its opposite ends to said leaves, substantially 20 as described and for the purpose set forth.

25 4. In a photographic-printing frame comprising a negative-holder, a removable back consisting of a pair of leaves, and means for retaining said leaves in contact with said negative, of a retractile spring connected at its opposite ends to said leaves; an angular trip device pivotally connected to one side of said negative-holder, and a spring retaining one arm of said trip device across one of the 30 leaves of said back and in the path thereof as it is lifted from the negative, substantially as described and for the purpose set forth.

35 5. In a photographic-printing frame comprising a negative-holder, a removable back consisting of a pair of leaves, and means for retaining said leaves in contact with said negative, of a retractile spring connected at

its opposite ends to said leaves, and a sucker mounted upon the inner face of one of said leaves, substantially as described and for the 40 purpose set forth.

6. In a photographic-printing frame, comprising a negative-holder, a removable back consisting of a pair of leaves, and means for retaining said leaves in contact with said negative, of a retractile spring connected at its opposite ends to said leaves; a sucker in the form of a soft-rubber saucer on the inner side of one of said leaves; an angular trip device pivotally connected to one side of said negative-holder, and a spring retaining one arm of said angular device across the said leaf and in the path thereof as it is lifted from the negative, substantially as described and for the purpose set forth.

55 7. In a photographic-printing frame comprising a negative-holder, a removable back consisting of a pair of leaves, and means for retaining said leaves in contact with said negative, of a retractile spring connected at 60 its opposite ends to said lever; an angular trip device pivotally connected to one side of said negative-holder and having the end of one arm offset; and a spring retaining said offset arm across one of the leaves of said back and in the path thereof as it is lifted from the negative, substantially as described and for the purpose set forth.

In testimony whereof I have affixed my signature in presence of two witnesses.

JAMES MICHAEL SMITH.
